(57) **CLAIM**

The ornamental design for compressor as shown and
described.

DESCRIPTION

FIG. 1 is a left side view of a compressor showing my new
design;

FIG. 2 is a right side view thereof;

FIG. 3 is a bottom view thereof;

FIG. 4 is a top view thereof;

FIG. 5 is a rear view thereof;

FIG. 6 is a front view thereof;

FIG. 7 is a top, front, left side perspective view thereof; and,
FIG. 8 is a top, front, right side perspective view thereof.
In the drawings, the broken lines depict portions of the
compressor that form no part of the claimed design.
